UNITED STATES PATENT OFFICE.

JOHN R. FISH, OF GRAND RAPIDS, MICHIGAN.

GRATE.

SPECIFICATION forming part of Letters Patent No. 248,155, dated October 11, 1881.

Application filed April 16, 1881. (No model.)

To all whom it may concern:

Be it known that I, JOHN R. FISH, of Grand Rapids, in the county of Kent and State of Michigan, have invented a new and Improved 5 Grate, of which the following is a specification.

The object of this invention is to provide an improved rocking grate, especially applicable to locomotive-engines, and designed to prevent 10 ice from collecting on the under side of the grate when the engine is running through snow.

Figure 1 is a sectional side elevation of the grate, with parts broken away to exhibit other 15 parts on line *x x*, Fig. 2. Fig. 2 is a sectional elevation on line *y y*, Fig. 1. Fig. 3 represents plans of an arched and a straight grate-bar.

Similar letters of reference indicate corresponding parts.

In the drawings, *A* represents an ash-pan having sockets *a* on its opposite edges, that serve as bearings for the journals *b b* on the ends of the grate-bars *B C*, respectively.

25 The grate-bars *B* are preferably double and provided on their sides with vertical parallel ribs *c*, that stiffen said bars *B*, render them less liable to warp, and by reducing the spaces between the bars when in position make it possible to use fine coal on the grate. These bars *B* are arched from their ends to their centers, as shown.

30 The grate-bars *C* are preferably double, and are provided with vertical parallel ribs *c'*, like those on the bars *B*, and serving the same purposes. These bars *C* are straight on both upper and lower faces.

40 Each bar *B C* is provided at one end with a depending leg, *D*, the extremity of which is provided with a journal, *d*, set at right angles thereto, which journals *d* are all entered into corresponding holes in the shaker-bar *E*, that extends through the ash-pan *A*, and is designed to pass up through the foot-board of 45 the engine (not shown) into the cab, to be within easy reach of the operator, whereby the grate may be shaken to free it from clinkers, crusts, and ashes.

It is designed to place one straight rocking

grate-bar *C* alternately with two or more 50 curved or arched rocking-bars *B*, as shown in the drawings, though I do not confine myself to this arrangement, so that, the said bars *B C* being journaled on the same level, the crowns of the bars *B* shall be considerably above the 55 level of the upper faces of the bars *C*, and consequently inserted in the fire on the grate, being thrust up, as it were, above the bottom of the fire that rests on the bars *C*. Hence the upper faces of the bars *B* become and continue 60 heated, and the heat of the fire, being conducted down through said bars *B*, prevents the accumulation of snow and formation of ice thereon to chill the cinders and clinkers on the grate and interfere with the draft through the 65 grate. It is evident, too, that with these upward-projecting bars *B* alternating with the straight bars *C* the rocking of the grate will more quickly and effectually break any crusts or clinkers that may form thereon.

70 The bars *B* have always curved or arched upper faces, but it is not necessary always that their under faces should be also curved.

I do not claim stationary grate-bars that are arched from ends to center, nor rocking grate-bars straight on their upper faces, as now in use on locomotive-engines; nor do I claim a 75 grate-bar arched or rounded transversely on its upper face, as none of these will accomplish the purposes of this invention; but,

80 Having thus fully described my invention, I claim as new and desire to secure by Letters Patent—

1. A rocking grate for locomotive-engine furnaces, consisting of the bars *B C*, having 85 journals *b* and vertical parallel ribs *c c'*, the bars *B* arched from their ends to their centers, and the bars *C* straight on both their upper and lower faces, as shown and described.

2. The combination, with a rocking grate, *B C*, of the depending legs *D*, having journals *d* at right angles to their extremities and connecting with a shaker-bar, *E*, extending through the ash-pan, as shown and described.

JOHN R. FISH.
